UNITED STATES PATENT OFFICE.

GEORGE W. GREEN, OF BEAUMONT, CALIFORNIA.

COMBINATION LOCK FOR PEN AND PENCIL SAFES.

Application filed September 1, 1923. Serial No. 660,659.

To all whom it may concern:

Be it known that I, GEORGE W. GREEN, a citizen of the United States, residing at Beaumont, in the county of Riverside and 5 State of California, have invented a new and useful Combination Lock for Pen and Pencil Safes, of which the following is a specification.

My invention relates to locking receptacles for pens and pencils and particularly to such as are fitted with tubular combination locks. Among the objects of my invention are, first, to provide a device of this nature that is relatively inexpensive and 10 suitable for the use of school children as a desk fixture; second, to furnish a simple and effective combination locking means that is not likely to become deranged in such service; and, third, to afford facilities for assembling the device in such a manner that it can not be taken apart or tampered with when closed and locked. Other objects and 15 advantages will appear hereinafter, and while I show herewith and will describe a 20 preferred form of construction, I desire to be understood that I do not limit myself to such preferred form, since various changes and adaptations may be made therein without departing from the spirit of my invention as hereinafter claimed.

My objects are attained by the construction illustrated in the accompanying drawing, in which—

Figure 1 is a side elevation of the complete device in closed and locked position;

Figure 2 is a vertical longitudinal section through the center, drawn to a larger scale; and,

Figures 3, 4, 5, and 6 respectively are cross sections taken on the line 3—3, 4—4, etc. of Fig. 2, looking in the direction indicated by the arrows. These cross sections are drawn on the same scale as Fig. 1.

Similar reference numerals refer to similar parts throughout the several views.

The device, as herein depicted, comprises a tubular body 7 formed with a central annular rim 8 at one end. The other end is closed by a cap 9. The cap is preferably 50 formed with feet so that it may be screwed to a desk, and a ring 10 with similarly formed feet is provided at the other end of the body. The cap and ring may be conveniently attached to the body by sweating. 55 The screws for fastening to the desk may

either be outside, as shown, or inside the tubular body where they are inaccessible when the device is closed. In the latter case the screws should be countersunk so as not to interfere with the rotation of cover 60 13.

Within the body, relatively near to the apertured end, is a discoidal partition 11 separating it into two compartments. The smaller of these is for housing the greater 65 portion of the locking mechanism, while the larger constitutes a receptacle for pens, pencils and similar articles. Partition 11 is permanently fixed within body 7 in any convenient manner as by sweating. 70

The upper half of the receptacle portion of the body is cut away, as at 12, to form an elongated rectangular aperture for access to its interior, and a similarly cut away tubular cover member 13 is adapted to rotate within the receptacle to act as a closure for the same. Cover 13 is conveniently rotated when desired by the handle 14. 75

Cover 13 may be locked in closed position, as here depicted, by lock bar 15. The 80 latter is slideable longitudinally and is adapted to engage a notch at 16 in the end of the cover. The lock bar works in a radial notch in partition 11, and is conveniently operated by a handle 17, projecting 85 through a slot 18 in the tubular body.

The locking mechanism is wholly assembled by means of an axial bolt 19, shouldered at 20 against partition 11, and rigidly attached thereto by the nuts 21. All of the 90 rotating parts of the locking mechanism revolve about this bolt as an axis.

The inner cylinder 22 is mounted directly upon bolt 19. It is formed with a knurled head 23 having a deep annular groove 24 95 forming an annular rim 25, of the same size and opposed to rim 8 on the end of the body. At the other end of this cylinder is a longitudinal notch 26, of such proportions that the lock bar 15 may be slid into it. On the 100 periphery of this member, adjacent the knurling, as at 27, is marked the numbers by which the combination is worked, the settings being made with the aid of a fixed point such as the indicating finger 28 attached to the body. 105

The tubular intermediate cylinder 29 is freely rotatable upon the inner cylinder, and within annular groove 24. It is formed with a notch 30, at one end, adapted to receive 110

the lock bar, and with a series of longitudinal slots 31, intermediate its ends, as indicated in Fig. 5. A resilient-band 32, with a flanged end and of such length as not to completely encircle this cylinder, is snapped on to the latter with the end flange engaging one of the slots 31. The selection of this slot determines one of the figures of the lock combination, and all of the slots are covered 10 by the band.

A tubular outer cylinder 33 is freely rotatable upon the intermediate cylinder. It has a notch 34 for the lock bar at one end, and the other end is slotted as at 35, in Fig. 5, and provided with a resilient end-flanged band 36 similar to that previously described, and for a corresponding purpose. The selection of the slot to be used for band 36 determines another figure of the lock combination and, as before, all of the slots in this 20 end of the cylinder are covered by this band.

Loosely surrounding the outer cylinder is a resilient band 37 with its ends 38 projecting through a slot in the tubular body of the device. This band is adapted to act as a 25 brake upon the outer cylinder by compressing the ends 38 together.

The tubular body is again slotted at 39 for the accommodation of the two light 30 pawls 40 and 41 pivoted by the pin 42 as shown in Fig. 2. These pawls respectively are adapted to engage the plain ends of bands 36 and 32 and thereby prevent the outer and intermediate cylinders from revolving 35 counter-clockwise. Pawl 40 is provided with a side lug 43 extending beneath pawl 41 so that the latter cannot drop to engage its band on the intermediate cylinder until pawl 40 has so dropped and engaged the 40 band on the outer cylinder.

The annular rim 8 on the body end, and the annular rim 25 on the head of the inner cylinder, are each provided with two diametrically opposed rectangular slots loosely 45 containing the small rectangular wedges 44, as shown in Fig. 2. Surrounding the circular flanges at this point, and confining the wedges, is a knurled collar 45, taper-bored at each end to properly engage the 50 respective wedges. Either pair of these wedges may be tightened against the intermediate cylinder by moving collar 45 longitudinally toward or away from the body of the device. In the former case the intermediate cylinder will be prevented from 55 turning. In the latter case the intermediate cylinder will be constrained to rotate when knurled head 23 is turned.

It will be evident from the foregoing that 60 the three cylinders may assume any angular position with respect to each other. Before the dialing of the combination is started therefore, the cylinders must be brought into proper angular relation for working 65 the combination. This is done by moving

collar 45 to the right and turning knurled head 23 backward (counter-clockwise) until pawls 40 and 41 have dropped and engaged, respectively, the outer and intermediate cylinders, and further, after moving collar 45 to its neutral position, until pointer 28 is opposite the starting number of the combination. The dialing is then proceeded with as follows:

First, move collar 45 to the right to engage the right hand wedges and turn head 23 to the right (clockwise) until the 2nd figure of the combination has been reached. Notch 34 of the outer cylinder will then be 70 in registry with the lock bar.

Second, compress brake handles 38 to hold the outer cylinder in this position, and continue to turn head 23 to the right until the 3rd figure of the combination has been reached. Notch 30 will then be in registry 80 with the lock bar.

Third, move collar 45 to the left, to hold the intermediate cylinder in this position, and turn head 23 either to the right or left until the 4th and final figure of the combination is reached. Notch 26 will then be in registry with the lock bar, and handle 17 may be moved to the right to slide lock bar 15 into all three of the cylinder notches, and thus release the cover.

It will be understood that, although it has been stated that intermediate cylinder 29 is freely rotatable upon the inner cylinder, and that outer cylinder 33 is freely rotatable upon the intermediate cylinder, the three cylinders in reality are in frictional engagement. This is due to the fact that the cylinders are fairly accurately fitted to each other with their surfaces in contact, and to the further fact that the weight of the intermediate and outer cylinders respectively is partially or wholly supported by the inner end of the inner cylinder. Rotation of the latter therefore serves 100 to rotate the others, unless they are prevented from turning in the manner described.

I particularly desire to emphasize the fact mentioned above that bolt 19, and nuts 21, maintain the assembly of the locking mechanism, and that the nuts are located within the lockable chamber of the device so that they cannot be tampered with when the device is locked. I prefer to make bolt 19 with a rounded countersunk head as shown, since this precludes the use of a wrench and discourages tampering; but the bolt in any event could not be removed by the mere use of a wrench on its head, in view of the lock nuts used at its inner end.

I claim as my invention:

1. A device of the character described comprising; a longitudinally slideable locking bar; concentric locking members in frictional engagement and having notches

adapted to receive said bar; external means for rotating one of the members for thereby bringing the notches of any of said members into registry with said bar; and clutch means for severally holding said members so registered.

2. A device of the character described comprising; a tubular shell; a longitudinally slidable locking bar within the shell; concentric tubular locking members in frictional engagement, within the shell, and having end notches adapted to receive said bar; external means for rotating the innermost member for thereby bringing the notches of any of said members into registry with said bar; and clutch means for severally holding said members so registered.

3. A device of the character described comprising; an integral tubular casing having one open end and a lateral aperture affording access to its interior; a rotatable closure for said aperture within said casing; a locking mechanism for said closure filling the open end of the casing; and a co-axial bolt adapted to effect the assembly of said casing and locking mechanism; said bolt being secured within the casing by means that are completely inaccessible when said closure is locked.

4. A device of the character described comprising; an integral tubular casing having one open end and an elongated lateral aperture affording access to its interior; a rotatable closure for said aperture within said casing adapted for being locked in closed position; a locking mechanism for said closure filling the open end of the casing and comprising concentric rotatable locking members in frictional engagement adapted for operation by means external to the casing; and a co-axial bolt effecting the assembly of said casing and locking mechanism; said bolt being secured within the casing by a nut that is completely inaccessible when said closure is locked.

5. A device of the character described comprising; an integral tubular casing having one open end and an elongated lateral aperture affording access to its interior; a rotatable closure for said aperture within the casing having an end notch whereby it may be locked in closed position; a locking bar adapted to engage said notch by longitudinal sliding; a locking mechanism filling the open end of the casing and comprising concentric rotatable locking members in frictional engagement and having end notches adapted to register and to receive said locking bar; means external to the casing for rotating said members; and a co-axial bolt effecting the assembly of said casing and locking mechanism; said bolt being secured within the casing by a nut that is

completely inaccessible when said closure is locked.

6. A device of the character described comprising; locking means including a plurality of nested cylinders with end notches therein; a locking bar adapted for entering said notches; means for rotating said cylinders to bring said notches into registry with said bar; and clutch means for severally holding said cylinders in registration with said bar; said cylinders being assembled within said device by means that are totally enclosed when the device is locked.

7. A device of the character described comprising; locking means including a plurality of nested cylinders with end notches therein; a locking bar adapted for entering said notches; means for rotating said cylinders to bring said notches into registry with said bar; dial means for determining when said notches are in registry with said bar; and clutch means for severally maintaining said registrations; said cylinders being assembled within the device by a bolt secured by lock nuts that are totally enclosed when the device is locked.

8. A device of the character described comprising; locking means consisting of a slideable bar and a plurality of independent nested cylinders in frictional engagement, and having end notches adapted to receive said bar; means for first bringing said cylinders into pre-determined angular relations, and for subsequently turning each cylinder through a pre-determined angle to bring its notches into registry with said bar; and clutch means for severally holding said members so registered.

9. In a device of the character described, means for changing the dial combination comprising; locking cylinders having a plurality of circumferentially arranged deformations on their peripheries; circumferentially incomplete resilient bands respectively covering and selectively engaging said deformations; and pawls pivoted to a non-rotatable portion of the device respectively adapted to engage the ends of said bands for angularly positioning the cylinders.

10. In a device of the character described, means for changing the dial combination comprising; locking cylinders having a plurality of circumferentially arranged longitudinal slots in their peripheries; circumferentially incomplete resilient bands respectively covering said slots and selectively engaging them by means of flanged ends on the bands; and pawls pivoted to a non-rotatable portion of the device respectively adapted to engage the plain ends of said bands for angularly positioning the cylinders.

GEORGE W. GREEN.
